PORTABLE ATOMIZER

Reme C. Seyforth, Shelby, Ohio

Application July 31, 1945, Serial No. 608,057

3 Claims. (Cl. 299—88.)

1

The present invention, relating as indicated to portable atomizers, has more particular regard to so-called pocket atomizers such as are largely used for spraying concentrated solutions of insecticide and cleaning compounds, perfumes and toilet liquids where a fine atomization is desired. It will be understood, however, that the improved features which characterize the invention is not limited to atomizers of any particular size or for any particular field of use.

One principal object of the invention is to provide a readily portable pocket size atomizer which can be readily carried on the person of the user, which will be capable of producing the desired and necessary fine atomization of concentrated insecticidal solutions, and that will be ready for instant use without catches that require to be released or complicated valves that are apt to get out of order.

A further object of the invention is to provide an atomizer of the type in question in which the container for the liquid to be atomized is readily detachable and may be made of glass, as is desirable where the atomizer is used with certain perfumes or other liquids which contain acids that act chemically on most metals. Such container at the same time serves as the actuating means for the device.

A further object is to eliminate the use of a so-called siphon tube, the liquid to be atomized being led directly from one end of the container to the discharge nozzle. By providing a seal for the latter the device is accordingly made leak-proof when in storage or while being carried about. The stream of air across such discharge nozzle will accordingly be all utilized to break up and atomize the liquid, none being required to raise or suck the liquid from the container.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a side elevation of an atomizer embodying my present improved construction;

Fig. 2 is a central longitudinal section thereof taken on the plane indicated by the line 2—2 of Fig. 1;

Fig. 3 is a similar section of a portion of the

device but on a somewhat larger scale in order better to show the detailed construction;

Fig. 4 is a perspective view of the plunger, whereby the air is compressed, together with attached liquid container, shown as removed from the casing;

Figs. 5 and 6 are transverse sectional views of the device taken on the planes indicated by the lines 5—5 and 6—6 respectively on Fig. 2; and

Fig. 7 is a sectional view on a larger scale of a recurred duct that leads from the inner end of the container to the discharge nozzle.

As clearly shown in Figs. 1 and 2, the main body of the atomizer consists of a cylindrical casing 1 that is closed at its one end, such end being desirably reenforced with a cap 2 so as to constitute what may be regarded as the base of the device, although it may be carried about, indifferently in any position, either vertical or horizontal. The opposite end of the casing is open, the edge of the opening being bent slightly inwardly to form a flange 3 against which a second shorter shell or sleeve 4 that closely fits within casing 1 is adapted to abut. The inner end of said sleeve is formed with an inwardly directed flange 5 (see Fig. 3) that is faced with a gasket 6 of rubber or like compressible material adapted to act as a seal, the latter being held in place by a second cylindrical flange 7 at the inner edge of said flange 5. Said flange 7 also serves to receive and guide the piston, as will presently appear, and at the same time keeps possible expansion of the gasket from binding and obstructing movement of said piston. The side wall of casing 1 is formed in its opposite sides with two longitudinal openings 8 and 9 which extend downwardly for some distance from points adjacent the lower edge of said gasket or sealing ring 6.

Reciprocally mounted in casing 1 between said sealing ring or gasket and the closed end of the casing is a hollow piston 10, shown in section in Fig. 2 and in perspective in Fig. 4. This piston carries the usual washer 11 at its lower end so as to be adapted to compress air in the portion 45 of the casing lying between the piston and the lower end of the casing. A compression spring 12 interposed between the piston and such lower casing end serves normally to move the former away from the latter.

The upper portion 13 of the piston is of reduced diameter so as to fit within the cylindrical flange 7 which by engagement with the offset on the piston acts as a stop, permitting the liquid discharge nozzle to press into the gasket to a predetermined depth only. Such portion is

formed with a vent opening 14 which upon movement of the piston against spring 12 will be exposed through a notch 7a in said flange and the aligned elongated opening 8 in the casing. A stud in the form of a screw 15 is secured to the opposite side of the piston so as to project into the other slot 9 in the casing wall, and thereby hold the piston against rotation while permitting reciprocal movement thereof within the longitudinal extent of such slot. The piston is also provided with a second vent opening 16 in its base whereby air may pass freely between its hollow interior and the compression chamber in the lower end of the casing. In other words, upon downward movement of the piston, i. e. movement toward the closed end of the casing, the air that is compressed in such lower portion of the casing passes through vent 16 into the hollow interior of the piston, still under pressure, and thence escapes in a forceful stream through the lateral vent 14. Upon reverse movement of the piston, air will enter through said last-mentioned vent into the hollow interior of the piston and thence flow through vent 16 to restore the normal pressure in the chamber therebelow.

Fixedly secured to the upper end of the piston is an oppositely directed threaded cap 20 that is adapted detachably to engage with a corresponding threaded end of a cylindrical liquid container 21. While the latter may be made of any suitable material, it will preferably be in the form of a cylindrical glass bottle, and in any event will be of such exterior diameter as to have a sliding fit within the flange 3 at the open end of casing 4 and will be of such length as normally to project beyond such end a distance equal to or preferably somewhat greater than the distance through which the piston 10 reciprocates. Said container constitutes the actuating means for the piston, being pressed inwardly to compress spring 12 and then moving outwardly when released under action of said spring, thus causing the exhaust and inflow of air through the piston, as described above.

Leading from a point within the cap 20 is a recurved duct 22 which extends downwardly into the hollow piston 10 and thence upwardly, terminating in a discharge nozzle 23 that is located closely adjacent the vent 14 in said piston thereby providing a passage leading from the interior of the liquid container 21 to the exterior thereof. The location of such nozzle, i. e. the point of termination of duct 22, as clearly shown in Fig. 2, will be short of the inner end of container 21; and such that when the piston is at its outer point of movement, said nozzle will be pressed against the sealing ring or gasket 6, thus effectively preventing any leakage of liquid from the container through the duct 22. However, upon forcing the piston inwardly by pressing against the outer end of the container, such nozzle will be unsealed and at the same time a jet of compressed air will be forced thereacross through the vent 14 in the piston.

With an atomizer constructed as described above, the liquid will always be at the point of discharge, i. e. at the nozzle 23, and the jet of air produced by the action of the piston, cutting across the point or orifice of the discharge of the nozzle, will break up and atomize the liquid as it comes out of the container. Withdrawal of liquid from the latter will of course produce a vacuum therein and upon the upstroke of the piston air will be drawn back through the nozzle and duct 22 into the container in amount

insufficient to replace the liquid withdrawn. The passage of this air back into the container is aided by having the inside diameter of the duct larger than the orifice at the nozzle (see Fig. 7), thus reducing friction and tendency of the liquid to congeal in the duct. Also by having the latter extend just into the container, the distance that the returning air travels is greatly reduced since it does not have to travel to or beyond the liquid level of the container. The operation is thus distinctly different from atomizers as heretofore constructed in which a siphon tube is employed, i. e. in which the liquid is siphoned from the container by the action of the air jet across the discharge nozzle. On the contrary, the liquid is simply drained out as through a hole in the bottom of the container. Furthermore, the provision in the piston of an air chamber having the air discharge outlet or vent made through its wall instead of conveying the compressed air by small diameter tube to such vent, there is much less possibility of foreign matter clogging the vent, which is necessarily of small diameter. In addition, such air chamber provides a convenient and advantageous point from which the necessary volume of air to atomize the liquid is directly delivered.

The present improved atomizer can be very economically and efficiently produced, since a minimum of machine work is required and the assembly of the parts is extremely simple. At the same time the construction of the atomizer lends itself readily to an improved method of testing before final assembly since this may be accomplished simply by attaching a container filled with liquid to the threaded cap and then supplying compressed air to the air chamber of the piston. In this way it can be readily determined whether proper atomization of liquid is being obtained, and the air chamber tested for leaks. There is furthermore no tedious drying and wiping required; since upon detaching the container used in such test the compressed air completely atomizes all the liquid that might remain in the discharge tube, and upon final assembly of the device with a fresh container the manufacturing operation is completed.

Obviously all of the liquid in a container, down to the last drop, may be used in operation of the device. The container can then be readily detached and refilled; or where in the form of a glass bottle, may be simply discarded and a filled container from stock substituted. As previously noted, the screw stud 15 will hold the piston against rotation, when a container is thus being screwed into, or unscrewed from the threaded cap 20. Of course one container may be exchanged for another without necessarily utilizing all of the contents of the first. For example, where used to atomize perfumes, different bottles containing different scents may be used from time to time as desired.

It will be understood that cap 2, which forms the closure for the compression chamber, is threaded or otherwise detachably secured to the corresponding end of the casing, a gasket being interposed for sealing purposes. For purpose of assembly or disassembly of the device it is merely necessary to remove screw 15 and this cap, whereupon the piston with appurtenant parts carried thereby, including the liquid container if desired, may be withdrawn through such end. However, if the container is removed along with the piston, the sleeve 4, which carries gasket 6, will likewise be removed therewith. It will be

noted that the exterior diameter of the liquid container is smaller than the interior diameter of the casing including such sleeve, so that an air space is left therebetween, thus insulating the container to a substantial extent against transfer of heat, e. g. from the user's hand when manipulating the device, or from other source. This is an important advantage where the liquid being sprayed contains a volatile ingredient.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In an atomizer, the combination of a casing having a closed lower end, a piston reciprocable in said casing adapted to compress air in the portion thereof adjacent such end, said casing having a lateral opening exposing a side portion of said piston and the latter having a vent in such portion for discharge of compressed air, a liquid container connected at its lower end to the upper end of said piston, a tube below said container having upwardly directed open ends respectively within and without said container, the ends of said tube being disposed below the level of the liquid in said container and providing the sole means of communication between the interior and exterior thereof, the end of said tube disposed without said container being adjacent to and transverse to such vent, said container serving as actuating means for said piston, a compression spring between said piston and casing, and a gasket in said casing above such last-named tube end, said spring yieldably urging said piston and container upwardly to effect sealing engagement between such tube end and said gasket.

2. In an atomizer, the combination of a casing having a closed lower end, a piston reciprocable in said casing adapted to compress air in the portion thereof adjacent such end, said casing having a lateral opening exposing a side portion of said piston and the latter having a vent in such portion for discharge of compressed air, a liquid container connected at its lower end to the upper end of said piston, a tube below said

5 container having upwardly directed open ends respectively within and without said container, the ends of said tube being disposed below the level of the liquid in said container and providing the sole means of communication between the interior and exterior thereof, the end of said tube disposed without said container being adjacent to and transverse to such vent, said container serving as actuating means for said piston, a sleeve in said casing provided with a radially inwardly extending flange above such last-named tube end and a cylindrical flange projecting downwardly from the inner extremity of such flange, a deformable gasket in the recess so defined by said casing and such flanges, and means for forcing such last-named tube end into sealing engagement with said gasket.

3. In an atomizer, the combination of a casing having a closed lower end, a member reciprocable in said casing adapted to compress air in the portion thereof adjacent such end, said casing having a lateral opening exposing a side portion of said member and the latter having a vent in such portion for discharge of compressed air, a liquid container carried by said member, the latter being provided with a passage having its ends below the level of the liquid in said container and respectively opening within and without said container and providing the sole means of communication between the interior and exterior of the latter, the outer end of such passage being located transversely adjacent to such vent, a gasket in said casing above the outer end of such passage, and a compression spring interposed between said member and casing, said spring yieldably urging said member upwardly to effect sealing engagement between the outer end of such passage and said gasket.
